UNITED STATES PATENT OFFICE.

CHARLES W. HUBBARD, JR., OF NEW YORK, AND CLARENCE C. VERNAM, OF HUNTINGTON, NEW YORK, ASSIGNEES TO BUD CIGARETTE CO., INC., OF NEW YORK, N. Y., A CORPORATION OF NEW YORK.

DESIGN FOR A BOX.

48,897.

Specification for Design.

Patented Apr. 18, 1916.

Application filed June 12, 1915. Serial No. 33,829. Term of patent 14 years.

To all whom it may concern:

Be it known that we, CHARLES W. HUBBARD, Jr., and CLARENCE C. VERNAM, citizens of the United States, residing, respectively, in the borough of Manhattan, city, county, and State of New York, and at Huntington, Long Island, in the county of Suffolk and State of New York, have invented a new, original, and ornamental Design for Boxes, of which the following is a specification, reference being had to the accompanying drawing, forming part thereof.

Figure 1 is a perspective view of the box closed; Fig. 2 is a side edge view; and Fig. 3 is an end edge view.

We claim:

The ornamental design for a box as shown.

CHARLES W. HUBBARD, JR.
CLARENCE C. VERNAM.
